CLAIM

The ornamental design for a front panel for computer data storage device enclosure, as shown and described.

DESCRIPTION

FIG. 1 is a top perspective view of the front panel for computer data storage device enclosure;

FIG. 2 is a rear elevation view of the embodiment shown in FIG. 1;

FIG. 3 is a top plan view of the embodiment shown in FIG. 1;

FIG. 4 is a bottom plan view of the embodiment shown in FIG. 1;

FIG. 5 is a side elevation view of FIG. 1;

FIG. 6 is another side elevation of FIG. 1; and,

FIG. 7 is a front elevation of FIG. 1.

The broken lines are shown in the views for illustrative purposes only and form no part of the claimed design.
